TABLE TOP CONSTRUCTION

Jacques Stanitz, Warren, Ohio, assignor to
 Mullins Manufacturing Corporation, Salem,
 Ohio, a corporation of New York

Application February 7, 1945, Serial No. 576,526

3 Claims. (Cl. 311—106)

1

The invention relates to a table top and trim construction and more particularly to the construction of a rigid, flat, work surface, table, counter, platform, sink drainboard and the like, having a top covering of material such as sheet linoleum, rubber, plastic, laminate and the like, and having a preferably curved front nose and a coved rear splashback.

Present day kitchens are equipped, in addition to a sink and a cabinet beneath the sink, with work tables, counters or platforms extending from one or both sides of the sink. These working surfaces may be formed integrally as a part of the sink drainboards, or may be the tops of various kinds of kitchen cabinets.

In either event, it is desired that the table tops be flat and relatively rigid, that they have a working surface, facing or covering which is softer than metal, that they have a preferably curved front nosing and a coved splashback, and that the working surface, nose and splashback present a smooth, uninterrupted surface free of ledges, shoulders, bumps or cracks from front to rear.

Considerable difficulty has been experienced in forming such table tops. Many parts and much hand work and fitting have heretofore been required. Prior art constructions, in order to avoid bending linoleum around and cementing it to a curved nose or cove surface which is unsatisfactory, have required a base member, a back member, separate linoleum strips for the base and back members, a nosing for the front of the base, another nosing for the top of the back, a cove piece, and hand fitting, cutting and notching of the linoleum for forming flush joints with the nosings and cove piece.

In prior art constructions using wood for the base members, any warping, swelling or checking of the wood produces cracks in the linoleum facing.

In other words, prior art table top constructions having rounded front edges and coved splashbacks involve many parts and considerable hand work and are consequently very expensive. Moreover, they are subject to failure, they have many joints, and they do not provide the desired degree of permanence.

Accordingly, it is a primary object of the present invention to provide a new table top construction for kitchen sinks, cabinets and the like.

Moreover, it is an object of the present invention to eliminate many parts heretofore required in the manufacture or construction of table tops

2

with soft working surface coverings and having rounded noses and coved splashbacks.

Also, it is an object of the present invention to eliminate hand work and numerous and expensive prior art operations and difficulties in the construction of such table tops.

Likewise, it is an object of the present invention to provide a table top construction in which a base member has secured thereto a flat, top linoleum facing, a nosing member, and a combined cove and splash back member.

Furthermore, it is an object of the present invention to provide a table top construction in which a base member is used that may be fabricated as a simple sheet metal stamping.

Also, it is an object of the present invention to provide a table top construction having a coved splashback in which linoleum is cemented in a simple manner only on a flat surface of the base 20 of the table top and with a flush joint between the surfaces of the linoleum and coved splashback.

Moreover, it is an object of the present invention to provide a table top construction in which a cove and splashback are combined as a single 25 member secured to the base of the table top, and which coved splashback member may be readily fabricated, and varied in height to change the general appearance of the completed table top structure.

Likewise, it is an object of the present invention to provide a table top construction in which a front nosing member is used that may be readily fabricated, and varied in shape to change the general appearance of the completed table top 30 construction.

Furthermore, it is an object of the present invention to eliminate several joints heretofore present in the exposed surface of table top constructions including a splashback and a cove.

Also, it is an object of the present invention to eliminate cementing linoleum upon curved surfaces of a table top having a coved splashback and rounded nose without involving additional joints in the completed structure.

Furthermore, it is an object of the present invention to provide a table top construction in which a combined cove and splashback is secured rigidly to the top surface of the base of the table top.

Also, it is an object of the present invention to provide a new table top construction for kitchen sinks, cabinets and the like incorporating the foregoing desiderata which may be fabricated at a factory by production methods to eliminate installation difficulties and reduce costs.

Finally, it is an object of the present invention to provide a new table top construction, which avoids prior art difficulties, satisfactorily solves problems existing in the art, and incorporates the foregoing advantages in a simple, effective and inexpensive manner.

These and other objects and advantages apparent to those skilled in the art from the following description and claims may be obtained, the stated results achieved, and the described difficulties overcome, by the devices, constructions, arrangements, combinations, sub-combinations, parts and elements which comprise the present invention, the nature of which are set forth in the following general statement, a preferred embodiment of which—illustrative of the best mode in which the applicant has contemplated applying the principle—is set forth in the following description and shown in the drawing, and which are particularly and distinctly pointed out and set forth in the appended claims forming part hereof.

The nature of the improvements in table top construction may be stated in general terms as preferably including a stamped sheet metal base member having a flat top formed with depending flanges terminating in inturned flanges entirely around the periphery of the flat top, preferably a sheet metal reinforcing channel member welded to the underside of the flat top within the confines of the depending flanges, a softer covering such as linoleum in sheet form cemented or bonded to the flat base top, the front and rear edges of the linoleum sheet being beveled, a channel shaped nosing member at the front edge of the base member having a beveled edge on its upper flange lapping the front beveled edge of the linoleum sheet, means securing the lower nosing flange to an inturned flange of the base member, an S-shaped splash back member including a curved cove portion, an upwardly extending portion, and a preferably curved top portion terminating in a downturned flange, the splash back member having a base portion provided with a beveled edge, the beveled edge of the splash back member overlapping the rear beveled edge of the linoleum sheet, means securing the base portion of the splash back member to the flat top of the base member, and binder means trimming the side edges of the base member and linoleum facing.

By way of example, a preferred embodiment of the improved table top construction is illustrated in the accompanying drawing forming part hereof:

Figure 1 is a perspective view of a kitchen cabinet unit provided with the improved table top construction;

Fig. 2 is a perspective view of a base member used in forming the improved table top construction;

Fig. 3 illustrates the step of cementing a flat linoleum facing sheet to the flat top of the base member of Fig. 2;

Fig. 4 illustrates the parts of Fig. 3 after the edges of the linoleum facing have been cut to size;

Fig. 5 is a fragmentary section looking in the direction of the arrows 5—5, Fig. 4;

Fig. 6 is a similar section looking in the direction of the arrows 6—6, Fig. 4;

Fig. 7 is a transverse section through the improved table top taken as on the line 7—7, Fig. 1, and

Fig. 8 is a longitudinal section taken on the line 8—8, Fig. 1.

Similar numerals refer to similar parts throughout the various figures of the drawing.

5 A kitchen cabinet is indicated generally in Fig. 1 provided with the improved table top construction designated generally at 1. Referring to Figs. 7 and 8, the improved table top includes a sheet metal base member 2 having a flat top portion 3 terminating at the side and rear edges in a downturned flange 4 and at the front edge in a preferably curved downturned flange 5. The flanges 4 and 5 preferably terminate in inturned flanges 6. Thus, the sheet metal base member has a substantially box form and is relatively rigid. Its rigidity may however be increased by spot welding or otherwise securing a channel reinforcing member 7 to the underside of the flat top 3 within the confines of the depending and inturned flanges 4 and 6.

10 A flat linoleum sheet 8 is cemented to the top of the upper flat portion of the base member 2 and the front and rear edges of the linoleum sheet 8 are beveled respectively as at 9 and 10.

15 The front of the base member 2 is provided with a nosing member 11 having a channel shape and the same curved contour as the contour of the depending base member flange 5. The edge of the upper nosing flange 12 is beveled at 13 to overlap the front beveled edge 9 of the linoleum facing 8 so as to firmly secure the front linoleum edge.

20 The lower flange 14 of the nosing member 11 is secured by any suitable means, preferably by bolts 15, to the inturned depending front base member flange 6.

25 At the rear of the table top, a combined cove and splash back member generally indicated at 16 is secured to the base member 2. The member 16 preferably has a base 17 preferably bolted at 18 to the flat top of the base member 2 and has a front tapered or beveled edge 19 lapping the rear tapered or beveled linoleum edge 10 to firmly secure the same to the base member.

30 Extending integrally upward from the base 17 of the splash back member 16 is an S-shaped portion including a curved cove portion 20 continuing in a substantially upright splash back portion 21 curving rearwardly at 22 to form an upper curved nose for the member 16 and terminating in a rear downturned flange 23.

35 Generally channel shaped members 24 may be provided along each longitudinal edge of the table top to bind and trim the base member 2 and linoleum facing 8.

40 In accordance with the present invention, each of the members from which the table top is constructed may be readily fabricated using production methods and at the same time the size as to length and width of the table top may be readily changed and the general appearance of the front nosing and of the coved splash back may be varied without introducing difficulties in effectively securing the softer linoleum facing to the base member.

45 Thus, the base member 2 is a simple sheet metal stamping which may be readily fabricated by production methods. The sheet metal channel member 7 likewise is a simple part and the same may be readily spot welded to the base member 2.

50 The linoleum facing 8 has a sheet form and is cemented flatwise to the top flat surface of the base member 2. Because no curved surface is involved in cementing the linoleum to the base member, the operation can be accomplished using heat or pressure or both in a single press; if de-

55

sired, and there is no cracking of the linoleum around any curved surface nor difficulty of cementing the linoleum to curved surfaces. Likewise the sheet metal base 2 is substantially rigid and cannot warp or swell like wood, and therefore will not crack the linoleum by expansion of the base member under normal conditions of use.

The nosing member 11 and splash back member 16 may be formed in a simple manner, each as an extruded metal section. Such parts may be brightly polished to present an attractive finished appearance and may also be readily secured to the base member. In changing the length of the table top, it is only necessary to change the length of cut sections of the extruded members 11 and 16. Likewise the trim members 24 are simple sheet metal stampings.

In manufacturing the improved table top, the base member 2 may be formed as a simple sheet steel stamping as illustrated in Fig. 2 and apertures 25 may be provided along the rear edge thereof for receiving the bolts 18. The reinforcing channel 7 may be welded to the underside of the flat top 3 of the base member 2. A sheet 8a of a softer covering material such as linoleum, rubber, plastic, laminate, or the like is then cemented flatwise to the flat top 3 of the base member 2 as illustrated in Fig. 3. Since both members are flat when cementing the sheet 8a to the base member 2, conditions are ideal for obtaining a satisfactory and uniform bonded joint throughout.

A jig then may be laid upon the parts illustrated in Fig. 3 having tapered front and rear guide slots. A cutting blade may then be inserted in and moved along each guide slot to form the tapered front and rear edges 9 and 10 for the linoleum facing 8, as illustrated in Fig. 4. Likewise, the side edges 26 of the linoleum sheet 8 may be cut or trimmed with a knife or shear in a simple manner.

The nosing member 11 may then be cut to length and bolted to the front edge of the base member 2 and the cove and splash back member 16 may be similarly cut to length and bolted to the rear of the base member 2. The side trim members 24 may then be secured in any desired manner to the side edges of the base member.

Thus, the completed structure has a facing of material softer than metal and has a curved front nosing and a coved splash back with an uninterrupted working surface from front to rear with only two transverse joints, one between the linoleum and nosing and one between the linoleum and splash back, and no linoleum is cemented to a curved surface.

The improved construction avoids any hand fitting, notching, grooving, or routing of the linoleum for forming flush joints; and numerous difficulties and expensive operations heretofore involved in forming a table top with a coved splash back and a rounded nose are eliminated. Likewise all hand work is avoided in fabricating the improved table top construction as distinguished from normal production operations.

Accordingly, the present improvements provide a table top construction which is simple and relatively inexpensive and which accomplishes all of the foregoing objects and avoids the described prior art difficulties.

In the foregoing description, certain terms have been used for brevity, clearness and understanding; but no limitations are to be implied therefrom beyond the requirements of the prior art, because such terms are utilized for descriptive

purposes herein and not for the purpose of limitation, and are intended to be broadly construed. Moreover the embodiment of the improved construction illustrated and described is by way of example and the scope of the present invention is not limited to exact details of construction of the various parts.

Likewise the construction is not limited to a table top for the kitchen cabinet illustrated because the table top construction may have any desired length and may serve as the drainboard for a sink which may be secured to the table top in any desired manner by forming a sink receiving aperture directly in the table top. Thus, a table top, platform, worktable, or the like, is included within the term "table top" as used herein. Moreover the facing may be of linoleum, rubber, plastic, laminate or other suitable relatively soft facing material; and the use of any such term includes all such terms.

Having now described the features of the invention, the manufacture of a preferred embodiment of the improved table top construction, and the advantageous, new and useful results attained thereby; the new and useful devices, constructions, arrangements, combinations, sub-combinations, parts and elements, and reasonable mechanical equivalents thereof, obvious to those skilled in the art, are set forth in the appended claims.

I claim:

1. In a table top construction, a sheet metal base member having a flat top portion formed at its edges with a downturned flange terminating in an inturned flange, a flat sheet of softer material cemented to said flat sheet metal top portion, the front and rear edges of the flat sheet being beveled, a channel-shaped metal nosing member having upper and lower flanges telescoped over the front flanged edge of the base member, means securing the lower nosing flange to the inturned front base flange, the upper flange of the nosing member having a beveled edge overlapping, engaging and securing the front beveled edge of the flat sheet, an S-shaped metal coved splashback member having a base portion resting on the rear portion of the flat top portion of the base member beyond the rear edge of the flat sheet, means securing the base portion of the S-shaped member to the sheet metal base member; said S-shaped member having a curved cove portion extending upward from the base portion, an upright portion extending upward from said curved cove portion, and a curved top nose extending from said upright portion; and the base portion of the S-shaped member having a beveled edge overlapping, engaging and securing the rear beveled edge of the flat sheet.

2. In a table top construction, a sheet metal base member having a flat top portion formed at its edges with a downturned flange terminating in an inturned flange, a flat sheet of linoleum cemented to said flat sheet metal top portion, the front and rear edges of the linoleum sheet being beveled, a channel-shaped metal nosing member having upper and lower flanges telescoped over the front flanged edge of the base member, means securing the lower nosing flange to the inturned front base flange, the upper flange of the nosing member having a beveled edge overlapping, engaging and securing the front beveled edge of the linoleum sheet, an S-shaped metal coved splashback member having a base portion resting on the rear portion of the flat top por-

tion of the base member beyond the rear edge of the linoleum sheet, means securing the base portion of the S-shaped member to the sheet metal base member; said S-shaped member having a concave curved cove portion extending upward from said base portion, a flat-surfaced upright portion extending upward from said cove portion, and a convex curved nose extending from said upright flat-surfaced portion; and the base portion of the S-shaped member having a beveled edge overlapping, engaging and securing the rear beveled edge of the linoleum sheet.

3. In a table top construction, a sheet metal base member having a flat top portion formed at its edges with a downturned flange terminating in an inturned flange, a channel reinforcing member secured to the underside of the flat top portion within the confines of the downturned flanges, a flat sheet of softer material cemented to said flat sheet metal top portion, the front and rear edges of the flat sheet being beveled, a channel-shaped metal nosing member having upper and lower flanges telescoped over the front flanged edge of the base member, means securing the lower nosing flange to the inturned front base flange, the upper flange of the nosing member having a beveled edge overlapping, engaging and securing the front beveled edge of the flat

sheet, an S-shaped metal coved splashback member having a base portion resting on the rear portion of the flat top portion of the base member beyond the rear edge of the flat sheet, means securing the base portion of the S-shaped member to the sheet metal base member; said S-shaped member having a curved cove portion extending upward from the base portion, an upright portion extending upward from said curved cove portion, and a curved top nose extending from said upright portion, and the base portion of the S-shaped member having a beveled edge overlapping, engaging and securing the rear beveled edge of the flat sheet.
